DRIVING MECHANISM FOR PUSH-BUTTON TUNERS

Clarence W. Wandrey, Wheaton, Ill., assignor to Zenith Radio Corporation, a corporation of Illinois

Application August 23, 1950, Serial No. 181,064

4 Claims. (Cl. 74—10.33)

1

This invention relates to an improved driving mechanism which may be conveniently utilized for releasably coupling the manual control member of a push-button tuner to an actuating shaft in such a tuner.

Push-button tuners are well-known to the art, and it has been considered desirable that some type of manual control member be included therein to tune a receiver incorporating the tuner to signal frequencies other than those selected by the push buttons. It has been usual practice to provide such a manual control member mechanically coupled to the actuating shaft of the tuner through a friction clutch arrangement. The friction clutch is so constructed that whenever a push button is depressed to actuate the tuner to a preselected signal frequency, the clutch automatically releases the manual control member from the tuner. This type of tuner has proven quite satisfactory with the exception that in the past it has been found difficult and expensive to construct a friction clutch which, when in its operative condition, establishes a positive drive between the manual control member and the actuating shaft of the tuner without undue slippage.

The present invention provides an improved driving mechanism which may be conveniently utilized for releasably coupling the manual control member of a push-button tuner to the actuating shaft thereof. The improved driving mechanism comprises a first bevel gear fixed to the actuating shaft of the tuner, a second bevel gear rotatably mounted on the actuating shaft, an apertured gear interposed between the bevel gears and having planetary gears rotatably mounted within its apertures and coaxing with the bevel gears. The second bevel gear is rotated by the manual control member and as long as the apertured gear is allowed to rotate freely no motion is translated to the first bevel gear fixed to the actuating shaft of the tuner. The mechanism also includes a latch so arranged that it is held out of engagement with the apertured gear whenever a push button is depressed, thus enabling the gear to rotate freely. However, when all the push buttons are in a released position, the latch engages the apertured gear preventing rotation thereof, and motion may be translated from the manual control member to the actuating shaft of the tuner.

The driving mechanism of this invention, as just indicated, finds ready application to push-button tuners and for convenience will be described in that connection. However, it will be

evident as the description proceeds, that the mechanism may have other independent applications corresponding to the various uses of the prior-art clutch mechanisms.

It is, accordingly, an object of this invention to provide an improved mechanism for releasably coupling apparatus to a driving means for actuation thereby.

A further object of this invention is to provide an improved driving mechanism for use in push-button tuners or the like for releasably coupling a manual control member to the actuating shaft of the tuner.

Yet another object of this invention is to provide such an improved driving mechanism that is simple and economical to construct, yet which operates with a degree of efficiency not present in usual prior art devices.

The features of this invention which are believed to be new are set forth with particularity in the appended claims. The invention itself, however, together with further objects and advantages thereof may best be understood by reference to the following description when taken in conjunction with the accompanying drawing, in which:

Figure 1 illustrates a push-button tuner incorporating the driving mechanism of the invention.

Figure 2 shows a portion of the driving mechanism as viewed from the section lines 2—2 of Figure 1, and

Figures 3—5 represent various components of the driving mechanism.

The push-button tuner of Figure 1 includes a supporting frame 10 which may be secured to the chassis or panel 11 of a radio receiver or the like. Frame 10 includes a pair of cross brackets 12, 13, spaced one from the other, and serving to support various push-rods 14 which are actuated by push-buttons 15 mechanically coupled to the push-rods by threaded studs 16 extending through panel 11.

The push-rods 14 have circumscribing springs 17, bearing against cross bracket 13 at one extremity and against stops 18 at the other, for urging the rods into a disengaged position with stops 19 bearing against cross bracket 12. Rods 14 individually include an adjustable arm 20, rotatably secured thereto for purposes to be described.

The tuner further comprises a carriage 21 rotatably mounted on frame 10 by means of an actuating shaft 22. The carriage 21 includes a pair of cross bars 23, 24 and a strip 25 mounted in end

portions 26, 27 of the carriage. The strip is rotatably mounted in the end portions and is mechanically connected by means of flexible connecting elements 29 to tuning cores 28a, 28b, 28c associated with tuning elements 30a, 30b, 30c mounted on frame 10, so that axial motion may be imparted to the tuning cores within the tuning elements.

The push-button tuner as thus far described is well-known to the art. When one of the push-buttons 15 is depressed, the corresponding adjustable arm 20 bears against one of the bars 23, 24 to rotate carriage 21 a preselected amount determined by the setting of the particular arm. This causes the tuning cores 28a, 28b, 28c to have a preselected tuning position within elements 30a, 30b, 30c corresponding to a predetermined signal frequency. When the push-button is released, it is returned to its original position by means of associated spring 17 but carriage 21 is maintained in its set position due to frictional engagement of actuating shaft 22 with supporting frame 10. The various arms 20 may be adjusted so as to rotate carriage 21 selected amounts when the various push-buttons are depressed, causing the tuning cores to have various preselected positions within tuning elements 30a, 30b, 30c.

The present invention provides a driving mechanism 31 for enabling the various tuning cores to be manually adjusted throughout the tuning range of elements 30a, 30b, 30c. This mechanism comprises a bevel gear or disc 32 having radial serrations and fixed to actuating shaft 22 of the tuner for rotation therewith, and a further bevel gear or disc 33 also having radial serrations and fixed to a driving shaft 34 rotatably mounted coaxially with shaft 22. An apertured gear or locking plate 35 is rotatably mounted on shaft 22 interposed between discs 32 and 33, and has a plurality of planetary gears 36 rotatably mounted in its apertures and coacting with the serrations in the discs 32 and 33.

A driving gear 37 is fixed to driving shaft 34 and engages a worm gear 38, the latter being actuated by a manual control knob 39 mechanically coupled thereto by means of a shaft 40. Driving shaft 34 and disc 33 are urged towards disc 32 by means of a spring 41 and retaining clip 42 so that there is positive engagement between planetary gears 36 and gears 32, 33.

The push-button tuner further includes a plate 43 pivoted to frame 10 and carrying a latch 44. A spring 45 is secured to plate 43 and cross bracket 13 so that latch 44 is normally urged into engagement with the peripheral teeth of gear 35 to prevent rotation of this gear. Moreover, plate 43 is so disposed that whenever one of the push-buttons 15 is depressed, the corresponding push-rod 14 bears against the plate and releases the latch. Figures 2-5 show in greater detail the various components of driving mechanism 31.

When all the push-buttons are in a released position as shown in Figure 1, latch 44, as previously stated, is urged into engagement with the peripheral teeth of gear 35 due to the action of spring 45. Rotation of knob 39 causes driving gear 37 and, therefore, driving shaft 34 to rotate. Rotation of driving shaft 34 causes gear 33 to rotate, and rotation of this gear drives the planetary gears 36. Under the above-described released condition of the push-buttons, latch 44 prevents rotation of gear 35, and the rotation of the planetary gears causes gear 32 and, thus, actuating shaft 22 to rotate. In this manner, 70

rotation of knob 39 causes carriage 21 to be rotated and cores 28a, 28b, 28c to be varied within tuning elements 30a, 30b, 30c. Whenever a push-button 15 is depressed, its corresponding push-rod 14 bears against plate 43 releasing latch 44. Carriage 21 is now free to rotate under the control of the push-buttons alone, since rotation of gear 33 merely rotates planetary gears 36 and gear 35 while gear 32 remains stationary. In other words, in this condition the free rotation of member 35 effectively prevents a driving force from being transferred from either one of the gears 32, 33 to the other. Therefore, carriage 21 may be freely rotated to a preselected position corresponding to the adjustment of arm 20 of a depressed push-rod 14.

A constructed embodiment of the invention has been found to operate with a high degree of efficiency. A positive drive is obtained between driving shaft 34 and actuating shaft 22 when latch 44 engages gear 35, and the slippage effect of usual prior art friction clutches is obviated for all practical purposes.

This invention provides, therefore, an improved driving mechanism for push-button tuners or for other purposes, which may be simply and conveniently constructed and yet which operates in a highly satisfactory manner.

While a particular embodiment of the invention has been shown and described modifications may be made and it is intended in the appended claims to cover all such modifications as fall within the true spirit and scope of the invention.

I claim:

35. 1. A tuning device for a radio receiver and the like comprising: a supporting frame; a series of push rods slidably supported by said frame; an actuating shaft rotatably supported by said frame; a carriage secured to said shaft for selective engagement and actuation by said push-rods to selected angular positions; a first bevel-gear mounted on said actuating shaft; a second bevel gear spaced from and supported coaxially with said first gear for rotation relative to said shaft; a locking member interposed between said gears; at least one planetary gear rotatably supported by said locking member in mechanical driving engagement with said first and second gears; a driving mechanism for rotating said second gear; a stop member supported from said frame for movement from a first position in which the stop member engages said locking member and completes a driving connection from said driving mechanism to said actuating shaft to a second position in which the stop member releases said locking member for rotation relative to said shaft; and a further member fixed to said stop member and operated by said push-rods for actuating said stop member from its first to its second position.

2. A tuning device for a radio receiver and the like comprising: a supporting frame; a series of push rods slidably supported by said frame; an actuating shaft rotatably supported by said frame; a carriage secured to said shaft for selective engagement and actuation by said push-rods to selected angular positions; a first bevel-gear mounted on said actuating shaft; a second bevel gear spaced from and supported coaxially with said first gear for rotation relative to said shaft; a locking member interposed between said gears; at least one planetary gear rotatably supported by said locking member in mechanical driving engagement with said first and second gears; a driving mechanism for rotating said sec-

ond gear; a stop member supported from said frame for movement from a first position in which the stop member engages said locking member and completes a driving connection from said driving mechanism to said actuating shaft to a second position in which the stop member releases said locking member for rotation relative to said shaft; a further member fixed to said stop member and operated by said push-rods for actuating said stop member from its first to its second position; and resilient means normally biasing said stop member to its aforesaid first position.

3. A tuning device for a radio receiver and the like comprising: a supporting frame; a series of push-rods slidably supported by said frame; an actuating shaft rotatably supported by said frame; a carriage secured to said shaft for selective engagement and actuation by said push rods to selected angular positions; a first bevel gear affixed to said actuating shaft; a second bevel gear spaced from and supported coaxially with said first gear for rotation relative to said shaft; a locking disc supported intermediate said gears for rotation relative to said shaft and having a plurality of apertures therein; a plurality of planetary gears rotatably supported in said apertures of said locking disc in mechanical driving engagement with said first and second gears; a driving mechanism for rotating said second gear; a stop member supported from said frame for movement from a first position in which the stop member engages said locking disc and completes a driving connection from said driving mechanism to said actuating shaft to a second position in which the stop member releases said locking disc for rotation relative to said shaft; and a further member fixed to said stop member and operated by said push-rods for actuating said stop member from its first to its second position; and resilient means coupled between said further member and said supporting frame for normally

biasing said stop member to its aforesaid first position.

4. A tuning device for a radio receiver and the like comprising: a supporting frame; a series of push-rods slidably supported by said frame; an actuating shaft rotatably supported by said frame; a carriage secured to said shaft for selective engagement and actuation by said push rods to selected angular positions; a first bevel gear affixed to said actuating shaft; a second bevel gear spaced from and supported coaxially with said first gear for rotation relative to said shaft; a peripherally toothed locking disc supported intermediate said gears for rotation relative to said shaft and having a plurality of apertures therein; a plurality of planetary gears rotatably supported in said apertures of said locking disc in mechanical driving engagement with said first and second gears; a driving mechanism for rotating said second gear; a plate pivoted to said supporting frame for actuation by said push-rods; and a latch rotatably supported by said frame and mechanically coupled to said plate for movement thereby from a first position in which the latch engages the peripheral teeth of said locking disc and completes a driving connection from said driving mechanism to said actuating shaft to a second position in which the latch releases the locking disc for rotation relative to said shaft.
